[57] CLAIM

The ornamental design for a compression sealing gasket for a liquid-tight fitting, substantially as shown.

DESCRIPTION

FIG. 1 is a perspective view taken from the front and right side of a compression sealing gasket for a liquid-tight fitting, showing my new design;

FIG. 2 is a top plan view thereof;

FIG. 3 is a front elevational view thereof;

FIG. 4 is a left side elevational view thereof;

FIG. 5 is a rear elevational view thereof; and

FIG. 6 is a bottom plan view thereof.
